UNITED STATES PATENT OFFICE.

EUGENE P. WOILLARD, OF SUGDEN, FLORIDA.

GAS OR VAPOR ENGINE.

SPECIFICATION forming part of Letters Patent No. 581,385, dated April 27, 1897.

Application filed May 14, 1896. Serial No. 591,530. (No model.)

To all whom it may concern:

Be it known that I, EUGENE P. WOILLARD, a citizen of the United States, residing at Sugden, in the county of Dade and State of Florida, 5 have invented certain new and useful Improvements in Gas or Vapor Engines; and I do hereby declare the following to be a full, clear, and exact description of the invention, such as will enable others skilled in the art to 10 to which it appertains to make and use the same.

My invention relates to improvements in gas and vapor engines, the object of the same being to so improve engines of this character that the gas, oil-vapors, or other explosive 15 mixtures employed as a motive agent will be utilized to their fullest extent; that a high range of expansion of the burned gases will be obtained; that a greater proportion of the heat will be converted into work than has heretofore 20 been obtainable; that a thorough mixing of the air and gases before ignition and a reliable ignition of the explosive charges is obtained, and that a regulation of the engine is effected by automatically varying the volume 25 of the explosive charges without varying the degree of inflammability.

The invention consists, essentially, of two high-pressure cylinders located one above the other, each provided with a piston having 30 a common piston-rod, which projects downwardly through the lower end of the lower cylinder and connects through a suitable pitman with the main drive-shaft, an auxiliary low-pressure cylinder having a piston moving 35 therein with a piston-rod connected thereto and to a crank-arm on said main drive-shaft, valve connections between said high-pressure cylinders and said low-pressure cylinder, a vaporizer and connections between 40 said vaporizer and each of said high-pressure cylinders, two explosion-chests, one for each of said high-pressure cylinders, having automatic-valve connections with said high-pressure cylinders, electric contact-points in each 45 of said explosion-chambers, connections between one of said points and a battery through a suitable spark-coil, a pair of reciprocating rods on the main drive-shaft, means connected with said rods for opening 50 and closing the valves in said explosion-chambers and said low-pressure cylinder at certain specified times, and an electric con-

nexion between said battery and one of said rods whereby contact is made with the other terminals in said explosion-chests and a spark 55 is produced therein.

The invention also consists in other details of construction and combinations of parts, which will be hereinafter more fully described and claimed. 60

In the drawings forming part of this specification, Figure 1 is a vertical central sectional view of my engine complete. Fig. 2 is a side elevation of the main shaft, showing the reversing mechanism connected therewith. Fig. 3 is a cross-sectional view of the same, showing the connection between said shaft and the reciprocating rods; and Fig. 4 is a detail in section. 65

Like reference-numerals indicate like parts 70 in the several views.

In constructing my device I employ two high-pressure cylinders 1, 2, located one above the other and each provided with pistons 3, 4, mounted upon a common piston-rod 5, passing through a suitable stuffing-box 6 in the cylinder-head 7, extending downwardly through the lower end of the cylinder 2 and having a cross-head 8 upon its lower end, which moves in the guides 9 in the framework. To the cross-head 8 is connected a pitman 9, which is attached at its lower end to a crank 10 on the main drive-shaft 11. Located at a point adjacent to the high-pressure cylinders 1, 2 is an auxiliary low-pressure cylinder 12, which has a piston 13 moving therein, having a piston-rod 14 extending from its underside through a suitable stuffing-box and provided with a cross-head 15 on its lower end, which moves in guides 16, secured to 80 the framework. The cross-head 15 is connected through a pitman 17 with a crank-arm 18 on the main drive-shaft 11. It will be observed that the crank-arms 10 and 18 are on diametrically opposite sides of the drive-shaft 85 11. The reason for this will appear later. Leading from the upper end of the cylinder 1 to the upper end of the cylinder 12 is a pipe or other suitable passage 19, which has a valve 20 at a point adjacent to the cylinder 12, whose stem 21 extends downwardly therefrom. A similar passage 22 extends from the under side of the cylinder 2 to the under side of the cylinder 12, the same also being pro- 90 95 100

vided with a valve 23 therein, whose stem 24 projects upwardly therefrom. The cylinder 12 is further provided with exhaust-valves 25 26, leading from its upper and lower ends, 5 respectively, and each provided with valve- stems 27 28. In the lower end of the high- pressure cylinder 1 is a suction-valve 29 upon the end of a pipe 30, leading from a suitable vaporizer through the governor 31. A similar 10 valve 32 is located at the upper end of the high-pressure cylinder 2 in the pipe 33, leading from said vaporizer. In connection with the foregoing devices I employ two explosion- chests 34 35, each provided with a suitable 15 water-jacket, as clearly shown in the drawings. From the upper end of the cylinder 2 leads a pipe 36, having a check-valve 37 at its lower end and connected through the automatic valve 38 with the interior of the explosion-chest 34. A similar connection-pipe 39, 20 having a check-valve 40 in its upper end, leads from the lower end of the cylinder 1 to the explosion-chest 35 and is provided with an automatic valve 41, as clearly shown. The 25 stems of both of the automatic valves 38 41 are each surrounded by a coiled spring, which normally holds said valves in their closed positions. The explosion-chest 34 leads into the upper end of the high-pressure cylinder 1 30 through an opening which is normally closed by an automatic valve 42, having a spring 43 surrounding the stem thereof and an adjusting-nut 44 upon the upper end, which permits the tension on the valve 42 to be regulated. 35 A similar valve 45 leads from the explosion-chamber 35 to the under side of the high-pressure cylinder 2. In the upper side of the explosion-chamber 34 is a purge-opening, which is normally closed by a valve 46, having 40 a stem 47 extending upwardly therefrom. The explosion-chest 35 is provided with a similar purge-opening, which is likewise closed by a purge-valve 48, having a stem 49 extending from the under side thereof.

45 The main shaft 11 is provided with two double cams 50 51, having a feather connection between said shaft and themselves, whereby a sliding movement on the shaft is permitted, but rotary movement independent of the shaft 50 is prevented. These cams are provided with double faces, which are connected through incline planes 52 52 for a purpose which will presently appear. Moving in engagement with the cams 50 51 are two rods 54 55, each 55 of which has a C-shaped extension 56 upon its lower end, which are provided with anti-friction-rollers 57. The said C-shaped extensions are adapted to surround the cams 50 51, so that upon the rotation of the shaft 11, 60 carrying said cams, a reciprocating motion will be imparted to the rods 54 55. The rod 54 has an arm 58 extending from its upper end and an arm 59 at an intermediate point, which are respectively adapted to engage at 65 the same time, upon the downward movement of the rod 54, the stem 27 of the valve 25 and the stem 24 of the valve 23. The said rod is

further provided with projecting arms 60 61, which are respectively adapted to engage, upon the upward movement of the rod 54, the 70 stem 21 of the valve 20 and the stem 28 of the valve 26. The rod 55 is provided with an arm 62 at its upper end and an arm 63 at a point near its lower end, which are adapted to engage the stem 47 of the valve 46 upon the 75 downward movement of said rod and the stem 49 of the valve 48 upon the upward movement of said rod. It should be stated here that the rod 55 is mounted in suitable guides or bearings in a stationary part of the framework and is surrounded by coiled springs 64 65, which engage a central stop or lug 66 on said rod and the beams or partitions 67 68 of said framework to normally hold said rod in its central position—that is, when said rod is 80 elevated through the medium of the cam 51 its lower end will be held in close connection with said cam, and when said rod is depressed through the same means the tendency of said springs will be to throw said rod upward. 85 The rod 55 is provided at a point near its upper end with an arm 69, which is loosely mounted thereon and held normally upward against a stop 70 by means of a coil-spring 71. It is also provided with a similar arm 72 near 90 its lower end, which is normally held downward against the stop 73 by a coiled spring 74. These arms are provided for the purpose of making electrical contact for the purpose of producing a spark on the inside of the explosion-chambers 34 35, as will presently appear. 95 75 represents an electrical contact-point extending to the inside of the explosion-chamber 34 and normally held in electrical connection with the battery 76 through the wire 77 and the spark-coil 78. A similar contact-point 79 extends to the inside of the explosion-chamber 34 and is slightly separated at its inner point from the end of the contact-point 75. The outer end of the contact-point 79 extends 100 out within the path of movement of the arm 69 on the rod 55. The said arm 69 is in electrical connection through the wire 80 with the other pole of the battery 76. The explosion-chamber 35 is provided with similar contact-points 81 82, the contact-point 81 being in circuit with the battery 76 through the wire 83 and spark-coil 78, and the contact-point 82 projecting out within the path of movement of the arm 72 on the rod 55, the 105 said arm 72 being in electrical connection with the other pole of the battery 76.

The two cams 52 53 on the shaft 11 are connected together through a rod 84, having the arms 85 86 thereon, which arms are provided with bifurcated lower ends, which are secured to collars 87 88, connected to the rear ends of the cams 52 53, respectively. An antifrictional ball-bearing is provided between the collars 87 88 and said cams. Stops 89 90 91 110 92 are provided on the shaft 11 to limit the forward and backward movement of the cams 52 53. The reversing-lever 84 is provided with a handle 93 upon its outer end and passes

through a clamping device 94, provided with a screw-wheel 95 thereon, by means of which said lever may be locked at any point to which it may be moved.

5 It is of course understood that by the arrangement just described the shifting of the cams 52 53 from their extreme rearward to their extreme forward position by means of a lever 84 will bring the rods 54 55 upon the opposite faces of the cams 52 53, and thereby change the phase of the reciprocation of said rods and the time of explosion in the chests 34 35, and thereby reverse the operation of the engine.

15 My invention has now been sufficiently described, it is thought, to enable the operation thereof to be readily understood. Starting then with the parts in the position in which they are shown in Fig. 1, its operation is as follows:

In Fig. 1 the pistons 3 4 in the cylinders 1 2 are supposed to be just starting on their upward stroke, with the rod 55 upon its downward stroke and the rod 54 upon its upward stroke. As soon as contact is made between the arm 72 and the contact-point 82 the circuit will be closed through the battery 76, the spark-coil 78, wire 83, contact-point 81, contact-point 82, and arm 72 back to the battery 76. A spark is produced at this moment in the explosion-chest 35, the explosion causing the automatic valve 45 to be opened and the expanded gases to be admitted into the high-pressure cylinder 2 on the under side of the piston 4 therein. An upward movement of said piston is thereby given. At the same time that the contact is made between the rod 72 and contact-point 82 the arm 62 on the upper end of the rod 55 is brought into engagement with the stem 47 of the purge-valve 46, which causes the burned gases of the last charge in the explosion-chamber 34 to be emitted therefrom. As the piston 4 rises the air and gas or vapor in the cylinder 2 are forced out through the check-valve 40 into the passage 39, and through the automatic valve 41 into the explosion-chamber 35. The upward movement of the piston 4 also carries with it the piston 3 by reason of the connection of said pistons with the common piston-rod 5. The upward movement of the piston 3 causes a suction of fresh gases and vapors from the vaporizer through the suction-valve 29 in the lower end of cylinder 1. At the same time the partially-expanded burned gases in the cylinder 1 are forced out through the passage 19 into the upper end of the low-pressure cylinder 12 through the valve 20, the said valve having been previously opened by reason of the engagement of the arm 60 on the rod 54 with the stem 21 of said valve, the opening of said valve 20 having simultaneously opened the exhaust-valve 26 in the lower end of the cylinder 12. The partially-expanded gases from the cylinder 1 are thereby utilized to their fullest extent in the auxiliary low-pressure cylinder 12. The power exerted by the

explosion in the chambers 34 35 is transmitted through the piston-rods 5 and 15 and suitable connections to the main drive-shaft 11, rotating the latter. A reverse action to that just described will be made upon the return movement of the rods 54 55, the parts brought into engagement being the duplicates of those referred to in the preceding description.

70

75

While my invention has been described in its preferred form, it is obvious that many modifications and minor changes might be made without departing from the nature or spirit of the invention or sacrificing any of its advantages. Such modifications and minor changes are clearly within the scope of this patent and are intended to be covered thereby.

Having now described my invention, what I claim as new, and desire to secure by Letters Patent, is—

1. In a gas or vapor engine, the combination of two high-pressure cylinders situated in line one with the other, pistons for said cylinders, a common piston-rod for said pistons, a drive-shaft and suitable connections between said piston-rod and said drive-shaft, an auxiliary low-pressure cylinder, a piston therefor, a piston-rod for said piston and connections between said piston-rod and said main drive-shaft, means for creating an explosion alternately on the operative sides of the pistons of the respective high-pressure cylinders, means for drawing air and gas into one cylinder while the piston in the other is being actuated and for forcing the partially-expanded gases from said inoperative cylinder to said low-pressure cylinder, substantially as and for the purpose described.

90

95

100

105

2. In a gas or vapor engine, the combination of two high-pressure cylinders situated in line one with the other, pistons for said cylinders, a common piston-rod for said pistons, a drive-shaft and suitable connections between said piston-rod and said drive-shaft, an auxiliary low-pressure cylinder, a piston therefor, a piston-rod for said piston and connections between said piston-rod and said main drive-shaft, two explosion-chests communicating respectively with the outer ends of said high-pressure cylinder, automatic valves in the passages between said chests and said cylinders, means for creating an explosion alternately in said chests at opposite ends of the strokes of said pistons, a vaporizer, pipes leading from said vaporizer to the inner ends of the respective high-pressure cylinders, suction-valves in the ends of said pipes, pipes leading from the inner ends of the respective high-pressure cylinders to each of said explosion-chests and pipes leading from the outer ends of said high-pressure cylinders to the outer ends of said low-pressure cylinder, and exhaust-valves in said low-pressure cylinder, substantially as and for the purpose described.

110

115

120

3. In a gas or vapor engine, the combination of two high-pressure cylinders situated in line one with the other, pistons for said cylinders,

- a common piston-rod for said pistons, a drive-shaft and suitable connections between said piston-rod and said drive-shaft, an auxiliary low-pressure cylinder, a piston therefor, a 5 piston-rod for said piston and connections between said piston-rod and said main drive-shaft, two explosion-chests communicating with the outer ends of said high-pressure cylinders respectively and means for creating 10 an explosion therein, automatic valves in the passages between said chest and said high-pressure cylinder, a vaporizer, pipes leading from said vaporizer to the inner ends of the respective high-pressure cylinders, pipes 15 leading respectively from the inner ends of said cylinders to said explosion-chests, automatic valves in said pipes, purge-valves in said explosion-chests and means for operating the same, pipes or passages leading from the 20 outer ends of said high-pressure cylinders to the outer ends of said low-pressure cylinder, normally-closed valves in said pipes, the said low-pressure cylinder being provided with exhaust-passages, valves in said exhaust-passages, 25 means for opening one pair of said valves to permit the passage of the partially-expanded gases from one of said high-pressure cylinders to said low-pressure cylinder and to exhaust the waste gases from said low-pressure cylinder, substantially as and for the purpose described.

4. In a gas or vapor engine, the combination of two high-pressure cylinders situated in line one with the other, pistons for said cylinders, 35 a common piston-rod for said pistons, a drive-shaft and suitable connections between said piston-rod and said drive-shaft, an auxiliary low-pressure cylinder, a piston therefor, a piston-rod for said piston and connections between 40 said piston-rod and said main drive-shaft, cams on said main drive-shaft, vertically-disposed rods engaging said cams and adapted to be reciprocated thereby, two electrical contact-points on one of said rods, an 45 electric battery and connections between said battery and said contact-points, two explosion-chests communicating respectively with the outer ends of said high-pressure cylinders, an automatic valve in the passage between 50 said chests and said cylinders, a contact-point or circuit-terminal extending into the interior of each of said explosion-chests, circuit-wires connecting said contact-point with said battery, a second contact-point in each 55 of said chests, the inner end thereof being located a slight distance from the circuit-terminal in said chest and the outer end thereof projecting in the path of movement of the contact-point on said rod, a vaporizer, pipes 60 leading from said vaporizer to the inner ends of said high-pressure cylinder, suction-valves in said pipes, pipes or passages leading from the inner ends of said high-pressure cylinders to said explosion-chests, passages leading 65 from the outer ends of said high-pressure cylinders into the outer ends of said low-

pressure cylinder, valves in said passages, exhaust-valves in said cylinder and means connected to the other of said rods whereby one of said exhaust-valves and one of the 70 valves in the opening between said high-pressure cylinder and said low-pressure cylinder are opened at the same time, substantially as and for the purpose described.

5. In an air and gas or vapor engine of the 75 character set forth, the combination with the main drive-shaft operated through suitable mechanism by the explosion of gas or vapor, of a pair of rods and suitable connections therewith, whereby said engine is controlled, 80 C-shaped extensions upon the lower ends of said rods, antifriction-rollers in the ends of said extensions, cams on said main shaft surrounded by said C-shaped extensions, the said cams being slidingly mounted on said 85 shaft but prevented from rotating independently thereof, formed with double cam-faces and an incline connecting said faces, stops for limiting the longitudinal movement of said cams, collars loosely fitting the rear end 90 of said cams, a reversing-lever having arms extending outwardly therefrom provided with bifurcated ends which surround and are connected to said collars, means for shifting said reversing-lever and means for securing said 95 lever in any position, substantially as and for the purpose described.

6. In a gas or vapor engine, the combination of two high-pressure cylinders situated in line one with the other, pistons for said cylinders, 100 a common piston-rod for said pistons, a drive-shaft and suitable connections between said piston-rod and said drive-shaft, an auxiliary low-pressure cylinder, a piston therefor, a piston-rod for said piston and connections between 105 said piston-rod and said main drive-shaft, a pair of cams on said main drive-shaft, rods 54, 55 mounted in suitable bearings in the framework engaging said cams, arms 58, 59, 60, 61 on the rod 54, arms 62, 63 on the 110 rod 55, contact-points 70 and 72 on the rod 55, springs for normally holding said contact-points in their outer positions, two explosion-chests communicating with the outer ends of said high-pressure cylinders, automatic valves 115 in the passages between said chests and said cylinders, a vaporizer, pipes leading from said vaporizer to the inner ends of the respective high-pressure cylinders, suction-valves in 120 said pipes, passages leading from the inner ends of said high-pressure cylinders to the respective explosion-chests, automatic valves in said pipes, passages leading from the outer ends of the respective high-pressure cylinders to the outer ends of said low-pressure cylinders, 125 valves in said passages adapted to be engaged by the arms 59, 60 on the rod 54, exhaust-valves in said low-pressure cylinder adapted to be engaged by the arms 58, 61 on the rod 54, a contact-point extending to the 130 interior of each of said explosion-chests, an electric battery, connections between one

5 pole of said battery and said contact-points and connections between the other pole of said battery and the contact-points 70, 72, the second contact-point extending to the inside of each of said explosion-chambers, the outer end thereof projecting out into the path of movement of the contact-points 70 and 72 and purge-valves in said explosion-chests which are adapted to be engaged respectively

by the arms 62 and 63 on the rod 55, substantially as and for the purpose described.

In testimony whereof I have signed this specification in the presence of two subscribing witnesses.

EUGENE P. WOILLARD.
